UNITED STATES PATENT OFFICE.

JOHN M. GRACE, OF CHICAGO, ILLINOIS, ASSIGNOR OF ONE-HALF TO
FRANCIS R. MURPHY, OF SAME PLACE.

CAR-BRAKE.

SPECIFICATION forming part of Letters Patent No. 293,319, dated February 12, 1884.

Application filed March 27, 1883. (No model.)

To all whom it may concern:

Be it known that I, JOHN M. GRACE, of Chicago, in the county of Cook and State of Illinois, have invented certain new and useful Improvements in Car-Brakes; and I do hereby declare that the following is a full, clear, and exact description thereof, reference being had to the accompanying drawings, and to the letters of reference marked thereon, which form a part 10 of this specification.

This invention relates to devices by which a simultaneous action of all the brakes throughout the cars of a train is derived from a single impulse or operation in such a manner that 15 the brake-operative devices of each car are under the control of the engineer on the locomotive; and it has for its object to produce a device by which the reciprocating movement of a piston in a steam-cylinder that is suspended below the tender or under the platform of 20 the locomotive will instantaneously and simultaneously apply or release the brake-shoes to or from the wheels in a train of cars.

Therefore my invention consists of the novel 25 devices and combinations of devices herein-after described and specifically claimed.

In the accompanying drawings, Figure 1 represents a sectional side elevation, and Fig. 2 a bottom view, of a car and the rear end of the 30 tender; and Figs. 3 and 4 are detail views on an enlarged scale.

Corresponding letters in the several figures of the drawings designate like parts.

A denotes the rear portion of the tender of a locomotive, below the floor-beams of which is secured a cylinder, B, that is closed on both ends, and has centrally in its rear head a stuffing-box for piston-rod *a* to project through. The piston *b*, that reciprocates in such cylinder, is secured to one end of rod *a*, and a head, *c*, is formed to the opposite end of such rod. This cylinder is to communicate with the locomotive-boiler through a steam-pipe that is in convenient reach of the engineer on the platform 45 of the locomotive, and is provided with a stop-valve. Live steam being admitted into the forward end of cylinder B, the piston *b* will be pushed rearward.

C is a freight-car, of any usual construction,

below the floor and underneath the couplings *d* 50 of which are arranged push-bars D D', having each a head, *e*, and being guided in hanger-brackets *f*. The heads *e* of these push-bars, thus projecting from under the car-body underneath the couplings, are on an elevation 55 corresponding with the elevation of head *c* of the piston-rod *a*. The inward end of each push-bar D is pivotally connected with the end of a horizontal beam, E or E', the opposite ends of which beams are pivotally connected to each 60 other by a bar or rod, F. Each beam E E' is supported and guided in a mortise-plate, G, that is rigidly secured under the car-body. These plates G have longitudinal slots *g*, and the beams E E' have each a trunnion, *h*, projecting at its middle from the top and bottom sides of the same into such slots *g* of plates G, in a manner that such beams are held centrally 65 in position, can vibrate in either direction, and have a limited longitudinal sliding movement 70 in the mortise-plates G.

H H are the car-wheels, I I' the brake-beams, and *i* the brake-shoes. To brake-beam I is pivotally coupled the brake-lever J, in the usual manner, one end of which brake-lever J, 75 by a rod, *o*, is coupled with the brake-beam I', while its opposite end, by a chain, *j*, is coupled with push-bar D', and by a chain, *p*, with the outward end of vibrating beam E'.

A pin or stud, *m*, is rigidly secured underneath the car-body, one for each vibrating beam E E' to shoulder against, which pin or stud *m* will form the fulcrum on which the beam E will be vibrated when forcing the push-bar D, that is connected therewith, toward the 85 center of the car, so as proportionally to increase the swinging movement of that end of beam E that is coupled to bar F, and thus to make up for any lost motion in the operating parts. This pin, stud, or shoulder *m* may be 90 made to form part of mortise-plates G.

When the engineer intends to stop the train, he will admit steam into cylinder B behind piston *b*, when such piston, moving rearward, will come in contact with the head *e* of push-bar D, 95 and will move such push-bar toward the center of the car, when beam E, butting against stud *m*, will vibrate and will pull bar F for-

ward, which again, being connected with beam E' of the opposite end of the car, will vibrate such beam to turn on its trunnions *h* in the end of slot *g* in mortise-plate G, and will push the bar D' rearward, to be brought in contact and communicate the same movements to the next rear adjoining car, and so on from car to car. The push-bar D', thus being moved outward or rearward, will pull the chain *j*, that will vibrate lever J and will draw the brake-shoes against the car-wheels, whereby the chain *p* will be slackened. When the locomotive is hitched to the opposite end of the car, the push-bar D' is brought in contact with head *c* of piston-rod *a*, and for applying the brakes such bar D' will be pushed to vibrate beam E', that will now shoulder against and swing on stud *m*, and the outward end of beam E', being connected with brake-lever J by chain *p*, will draw the brake-shoes against the car-wheels, whereby chain *j* will be slackened. In this manner, according to the direction the train is coupled to the locomotive, either chain *j* or *p* will vibrate the brake-lever and will apply the brakes. The brakes can thus be simultaneously and instantaneously operated throughout the train by the motion of the steam-piston, no matter to which end of a train of cars the locomotive is coupled, and whether such train is pulled forward or is being pushed backward by the locomotive.

The steam-cylinder B may as well be secured to the platform of the locomotive, and push-bars arranged underneath the tender that will transmit the movement of the piston to the push-bars of the cars.

With this device the bar or rod F is only ex-

posed to a tensile strain, and therefore it can be made of common bar-iron.

The device herein described is simple in its construction and reliable in its operation. The arrangement of the brake-shoes in the car-trucks being of the usual construction, they need not to interfere with the ordinary operation of the brakes by hand.

45

What I claim is—

1. In the car-braking device herein described, and in combination with push-bars D D' and connecting-bar F, vibrating beams E E', having trunnions *h*, and mortise-plates G, having slots *g* and shoulder-studs *m*, all substantially as and for the purpose set forth.

2. The combination, with steam-actuated piston *b*, of push-bars D D', vibrating beams E E', provided with trunnions *h*, connecting-rod F, and mortise-plate G, provided with slot *g* and stud *m*, the parts arranged and operating substantially as described and shown.

3. The vibrating beams E E', provided with trunnions *h*, and connected by bar F, in combination with brake-beams I I' and mortise-plate G, said plate provided with slot *g* and stud *m*, and the beams E' and I being suitably connected, the several parts being operated by steam-actuated piston *b* and push-rods D D', as described and shown.

In testimony that I claim the foregoing as my invention I affix my signature in presence of two witnesses.

JOHN M. GRACE.
